SHIRT

Jerry J. Calhoun, Sr., 393 Lewis Blvd. SE.,
St. Petersburg, Fla. 33705

Filed May 23, 1972, Ser. No. 256,204

Term of patent 14 years

Int. Cl. D2—02

U.S. Cl. D2—208

FIG. 2.

FIG. 1.

FIG. 3.

FIG. 4.

FIG. 5.

FIG. 1 is a front perspective view of a shirt showing my new design, the broken line showing of a necktie being for purposes of illustration only;

FIG. 2 is a rear perspective view thereof;

FIG. 3 is an enlarged fragmentary perspective view of a portion of the collar thereof;

FIG. 4 is a front perspective view of the shirt; and

FIG. 5 is a rear perspective view thereof.

I claim:

The ornamental design for a shirt, substantially as shown and described.
